NON-REFILLABLE BOTTLE.

1,169,498.

Specification of Letters Patent. Patented Jan. 25, 1916.

Application filed March 4, 1912. Serial No. 681,403.

To all whom it may concern:

Be it known that I, JOSEPH D. LACROIX, a citizen of the United States, residing in Baltimore city and State of Maryland, have 5 invented certain new and useful Improvements in Non-Refillable Bottles, fully described and represented in the following specification and the accompanying drawings, forming a part of the same.

10 This invention relates to improvements in so-called non-refillable bottles.

The invention has reference to the valve and baffle mechanism thereof.

As to the former, the object of the present 15 invention is to provide a valve mechanism which in certain respects will be more satisfactory in operation than prior valve mechanisms.

As to the latter, the object of the present 20 invention is to provide an effective baffle mechanism which can be more economically produced and combined with the bottle neck.

In the accompanying drawing—Figure 1 is a vertical sectional elevation of a bottle 25 equipped with the present improvements in their preferred forms; Fig. 2 is a plan view of the bottle; Figs. 3 and 4 are horizontal sections thereof on the lines 3, 4, respectively, of Fig. 1, and Fig. 5 is a view similar to Fig. 1 but with the bottle in tilted or pouring position.

Referring to said drawing, 1 represents the bottle bdy and 2 a bottle neck secured thereto by a metal band 3, portions of which 35 are spun into depressions in the neck 2, and a neck section 4 on the bottle body 1 in a manner which is now well known. In the commercial production of a separable bottle neck like neck 2, it has been usual to make it 40 in two separably molded longitudinal sections, as shown and described in Patent No. 1,016,112, granted to Lacroix and Switzer January 30, 1912. It was so made in order to provide for the stationary baffle mechanism in the bottle neck. I have discovered, 45 however, that it may be made in a single molded piece or section, by molding a part, as the inwardly projecting flange 5, integrally with the bottle neck, and separately 50 molding the balance of the baffle, as plug 6, which is then introduced into the bottle neck above the valve chamber, as shown, and cemented therein by means of suitable cementitious material or subsequent baking of 55 the neck, the neck and this plug being pref-

erably of porcelain. Accurate positioning of the plug 6 is insured by the provision of lugs 7 depending from flange 5 which engage the upper edges or surface of the annular shoulder or flange of the plug as it 60 is shoved into the bottle neck. The inner surface of the bottle neck, in line with and below the plug 6, is corrugated or ribbed vertically, as shown at 8, these ribs or corrugations providing liquid passages past the 65 plug, the outer surface of which contacts with these corrugations or ribs, as shown. The plug 6 is provided with a post 9 crowned by a disk 10 extending upwardly beyond the flange 5, there being sufficient 70 space between the flange and said post for the passage of liquid, while at the same time the post and its disk 10 occupy such a relation to the inner surface of the bottle neck and flange 5 as to effectually prevent the insertion, into the lower part of the bottle neck, of a wire or other valve-tampering implement. This is further provided against by the provision of a depression 11 in the 75 upper face of the plug 6.

Coming now to the valve mechanism, the valve 12 is substantially the same as that shown and described in the aforesaid Lacroix and Switzer patent, being of cup shape conical form and resting at its lower edge 80 on valve seat 13 so as to tilt freely thereon in its opening and closing movements. The improvement in the present case as to the valve mechanism resides in the valve-controlling weight 14. Its lower end or major 85 portion, or weight proper, is, as will be observed, inclined slightly downwardly, and it has a contracted rounded upper portion or protuberance 15, fitting loosely in, and in operation coacting with, the sides of the 90 socket 16, having preferably the same shape. This protuberance 15 is ribbed vertically to minimize the area of surface contact between it and the walls of recess 11. Socket 16 has, at its inner end or bottom, a rounded cavity 95 17 for receiving the upper end of protuberance 15 and on which the latter is to rock, as the bottle is tilted to and from pouring position. Although in construction and action the cam-like weight 14 of the present 100 case is generally of the same type as the weight of the aforesaid Lacroix and Switzer patent, it is, because of certain peculiarities in its construction, different in operation 105 from and more satisfactory in actual com- 110

mercial use than the latter. Normally it occupies the position shown in Fig. 1. As the bottle is tilted from that position toward a horizontal position, the weight 14 bears 5 against the valve holding it closed until the bottle is tilted beyond the horizontal. At that instant the protuberance 15, coacting, at approximately its base, with the base of the socket 16, causes the weight 14 to tilt, at 10 what is then its upper side, abruptly away from the valve, the valve-engaging portion of the weight, in so tilting moving radially outward from the center to what is then the upper side of the valve, which is then tilted 15 open, as shown in Fig. 5. Tilting of the bottle beyond this position will result in bodily movement (limited by plug 6) of the weight 14 away from the valve seat, and consequent bodily movement of the valve so as to more 20 fully open the passage between it and the valve seat. As the bottle is restored to upright position, the action of the weight is, of course, reversed. In this movement, as soon as the bottle reaches horizontal position, 25 weight 14 tilts toward the valve engaging it first near what is then its upper side and then moving radially inward toward its center, thus moving it, with a cam-like action, to its seat. In both operations it will be observed that the weight 14, through its protuberance 15 rocks or turns freely in the 30 socket 16, and that in addition to such movement the weight has an abrupt tilting valve-opening or valve-closing movement effected. 35 by the engagement of protuberance 15 with the base or lower edge of socket 16.

What is claimed is:—

1. In a non-refillable bottle, the combination, with a bottle body having a neck-portion, a separate valve seat member arranged to rest on the body portion of the bottle, and a neck-portion having a rebate at its lower end within which the valve seat is recessed, and having a plurality of inward projecting 40 arms at its upper portion below the mouth, of a baffle device arranged to be introduced from the lower end of the neck portion and

to be secured with its upper surface in contact with the inward projecting arms, said baffle device having an upward extending 50 portion projecting into the upper neck portion of the bottle and provided with an outward extending flange, means for securing the neck portion to the bottle and valve mechanism below the baffle and arranged to close 55 the valve seat opening.

2. In a non-refillable bottle, the combination, with a bottle body having a neck-portion, a valve seat member arranged to rest on the body portion of the bottle, and a neck-portion arranged to engage the valve seat, 60 said neck-portion having a plurality of inward projecting arms at its upper portion and below its mouth, of a baffle device arranged to be introduced from the lower end 65 of the neck-portion and to be secured with its upper surface in contact with the inward projecting arms, said baffle device having a socket in its lower face, a weight having an enlarged lower end with a convexly curved 70 bottom and having a contracted cam-like projection at its upper end arranged to enter and rock in the socket, and a valve arranged to rest on the valve seat and having an upwardly sloping periphery on which it may 75 tilt against the inside of the neck-portion, the cam-like projection and socket being so constructed and arranged relative to each other that as the bottle is tilted said weight will rock freely in said socket and slidingly 80 engage the valve in radial lines between the center of the valve and that side of the valve which is uppermost in the tilted position of the bottle, and also, at or about the horizontal position of the bottle, will be abruptly 85 tilted to or from the valve as the case may be.

In testimony whereof, I have hereunto set my hand, in the presence of two subscribing witnesses.

JOSEPH D. LACROIX.
